Primary Examiner — Robert M Spear*Assistant Examiner* — Ryan Harvey(74) *Attorney, Agent, or Firm* — John C. Shepard(57) **CLAIM**

The ornamental design for a rebound training device frame, as shown and described.

DESCRIPTION

FIG. 1 is a top, back, left side perspective view of a rebound training device frame showing my new design;

FIG. 2 is a front elevational view of the rebound training device frame shown in FIG. 1;

FIG. 3 is a right side elevational view of the rebound training device frame shown in FIG. 1;

FIG. 4 is a back elevational view of the rebound training device frame shown in FIG. 1;

FIG. 5 is a left side elevational view of the rebound training device frame shown in FIG. 1;

FIG. 6 is a top plan view of the rebound training device frame shown in FIG. 1;

FIG. 7 is a bottom plan view of the rebound training device frame shown in FIG. 1;

FIG. 8 is a bottom, front, right side perspective view of a rebound training device frame showing my new design; and, FIG. 9 is a top, back, left side perspective view of the rebound training device frame shown in FIG. 1 with the hand holds repositioned to illustrate a position of use.
